COMBINATION GAME SET

Samuel John Stanton, Chicago, Ill.

Application November 23, 1942, Serial No. 466,691

10 Claims. (Cl. 312—146)

This application relates to the general class of poker chip racks, and more particularly to a series of poker chip holders originated by the present inventor.

The general characteristics in this unit as in the other of this series are uniqueness in structural composition, compactness, style, aptness, simplicity of design and adaptability to quantity production.

The present novelty, like the one disclosed in my application Serial No. 413,524 filed October 31, 1941, comprises a housing element and tray elements. But the tray elements, in this instance, disclose more differentiating elements within themselves and the unit incorporating them discloses more differentiating elements in its combination.

The result is a unit of a size practically the same, incorporating twice as many trays.

This new combination as well as the unique tray elements which go into its composition are treated quite extensively in the following text in combination with the annexed drawings which, like the text, are made a part of this application, terminating in a series of conventional claims.

In the drawings as figures:

Fig. 1 is a perspective view of one of the forms of applicant's poker chip unit.

Fig. 2 is a transverse cross section of Fig. 1, the dotted lines showing the drawer element partially out of the housing.

Fig. 3 is a longitudinal cross section of Fig. 1 taken on line 3—3, Fig. 2, on line 3—3, Fig. 4.

Fig. 4 is a horizontal cross section of the characteristic drawer element taken on line 4—4, Fig. 3.

Fig. 5 is a perspective view of the housing element, the top partially broken.

Fig. 6 is a perspective view of the drawer element, the front partially broken away.

Fig. 7 is a cross section of Fig. 1 taken on line 7—7 showing a view of tray elements and the drawer element in engaged or interlocked position inside the housing element.

Fig. 8 is a cross transverse section of a stack of tray elements in engaged or interlocked position outside the housing element.

Fig. 9 is a longitudinal cross section of tray elements in engaged or interlocked position outside the housing element.

Figs. 10 and 11 are perspective views of tray elements showing engaging or interlocking elements.

Fig. 12 is a fragmentary perspective view of a corner of the drawer element.

Fig. 13 is a perspective view illustrating a slightly modified form of the invention;

Fig. 14 is a horizontal section of a form of the invention disclosed in Fig. 13, taken on the line 14—14 of Fig. 15.

Fig. 15 is a vertical longitudinal section taken on the line 15—15 of Fig. 14.

Fig. 16 is a fragmentary perspective view of a corner of the drawer shown in Fig. 13.

Fig. 17 is a perspective view of the housing element of the form shown in Fig. 18.

Fig. 18 is a perspective view of the drawer shown in Fig. 13.

Fig. 19 is a perspective view of a locking bar used in connection with the modified form of the invention illustrated in Fig. 13.

Fig. 20 is a vertical cross section taken on the line 21—21 of Fig. 13 with the tray elements removed.

Fig. 21 is a vertical cross section taken on the line 21—21 of Fig. 13.

Fig. 22 is a central vertical longitudinal section taken through a stack of the tray elements.

Fig. 23 is a vertical cross section taken on the line 23—23 of Fig. 22.

Fig. 24 is a perspective view of one of the tray members and a tray element detached therefrom, illustrating certain interfitting connections between them; and

Fig. 25 is a perspective view of the two members of a tray element separated from each other.

In the drawings in more detail, where like parts are indicated by like numerals:

Numerals 10 points to the unit as a whole and 11 indicates the drawer element.

Numerals 12 and 13, best seen in Figs. 10 and 11, indicate the tray elements. The bottom view of Fig. 10 shows elements 12 and 13 as parts of a compartment unit. The open view of the elements in Fig. 11 shows them as individual tray elements. This dual phase of the tray elements is one of the unique characteristics of the present invention. Inside the housing, they form into compartments wherein the chips are held securely. The compartments, consisting of two tray elements each, combine uniquely into stacks. This makes it possible to put in 10 compartment elements, used as 20 tray elements, within the narrow limits as suggested in Fig. 1.

50 This is important. Where the tray elements are used as racks by players, it is essential to have enough racks for the chips in circulation and for those in reserve. Only by storing the tray elements face to face snugly embracing stacks of chips, that is, as compartments within the

housing, is it possible to have a number of racks sufficient for the dual purpose.

Numerals 14 to 17, inclusive, indicate the walls of the framework or housing, a very simple, box-like cabinet.

Numerals 18-18', Figs. 2 and 3, show a strip along the back part of the framework or housing 14, 15, 16 and 17. It is extended sufficiently low to engage the tray elements, when in stack formation within the housing. This is best shown in Fig. 7.

Numerals 19 and 20, Fig. 5, show rail or track elements for the drawer element. These may be extended clear across the housing, in which case they would constitute a wall dividing the housing into compartments—not shown in present drawings.

Numerals 21 to 24, inclusive, indicate the walls of the drawer element, a box-like unit fitting snugly within the housing element 14, 15, 16 and 17, where it slides in and slides out over the rail elements 19 and 20.

Numerals 25 and 26, Fig. 6, indicate partitions dividing the drawer element 11 for convenient playing card compartments. Numeral 27 shows the bottom of one of these compartments. Numerals 30 and 31 show openings in the bottoms of the other two compartments. Numerals 28 and 29 indicate borders around the openings 30 and 31 sufficiently wide to support the playing cards within the compartments. The openings make it possible to push the cards out of the compartments wherein they lie snugly embraced.

Figs. 2 and 6 disclose one way of engaging the drawer element 11 with the housing element, 14, 15, 16 and 17. This is a latch 33-34, 34 being the receiving trap or catch element thereof and 33 the inserting or entrapped element thereof. One of these elements is attached to the strip element 18, Fig. 5, and the other to the drawer element within the compartment 32, Fig. 6. These two elements engaged with each other hold the drawer element securely within the housing element.

These two elements 33-34, may be just the plain parts that constitute the familiar catch in most bathroom medicine cabinets.

Numerals 35 to 39, Figs. 7 and 11, inclusive, indicate the walls of a tray element. A tray element is rectangular in shape, in general effect a box-like unit. It is sufficiently formed to embrace a stack of chips. The two tray elements engaged "face to face" as shown in Fig. 10 embrace the stack so that the stacks of chips are edgewisely in contact with all longitudinal walls of the closed compartment, that is in contact with the bottom wall elements 39 and 54 (Figs. 11 and 8), as well as with side wall elements 35, 36, 45 and 46.

Numerals 42 and 43, Fig. 11, show projections on the rim or walls, 35 and 36, of one part of the compartment element. Numerals 51 and 52 show notches on the rim or walls 45 and 46 of the other part of the compartment element. These projections fit substantially within the corresponding notches.

Numeral 44 shows projections on the end of wall 37. Similarly on wall 38. Numeral 53 shows a notch on end wall 47. Similarly on end wall 48. The tray elements are so contrived that when 42 and 43 fit into 51 and 52, 44 fits correspondingly into 53, so that when the tray elements are brought face to face, or rim to rim, the projections fitted into their respective notches will hold

the tray elements interlocked laterally and longitudinally. Each compartment element thus comprises two parts, that is, two tray elements combined rim to rim or face to face as a unit compartment element.

Numerals 54 indicates the bottom of tray element 12, Fig. 11, and numeral 55 is a projection element on the bottom of tray element 13, Figs. 10 and 8. Numeral 56 indicates a notch element in the top of tray element 12, Figs. 8 and 10. Projection element 55 fits substantially into notch element 56, Fig. 10.

When the compartment elements are stacked as shown in Figs. 7, 8 and 1, these elements 55 and 56, Figs. 1, 8 and 10, engage or interlock laterally and longitudinally the compartment elements into stack elements.

Numerals 57 indicates a beveled edge on the tray element 13. Numeral 58 indicate a beveled edge on the top of tray element 12. These edges beveled to correspond serve as another means of engaging the compartment elements laterally and longitudinally.

Numeral 21' in Figs. 2, 6 and 7 shows an apron element as a development of wall 21. When the drawer element 11 is inserted as in Figs. 1 and 2, into the housing or framework 14, 15, 16 and 17, Fig. 7, the compartment elements as stacks become entrapped or engaged between the elements 21' and 18', Figs. 2 and 7, the elements 60 and 18 resting on top of the stack elements. This locks or engages the stacks vertically and transversely within the framework or housing element 14, 15, 16 and 17.

Fig. 1 shows five such stacks contiguous to each other, the end stacks contiguous to walls 16 and 17 within the framework 14, 15, 16 and 17.

When the drawer element 11 is inserted into the framework 14, 15, 16 and 17, as shown in Figs. 1 and 2, the drawer becomes engaged within the housing by means of the latch 33-34, the stacks become engaged therein by means of the elements 21' and 18' transversely, longitudinally by means of the walls 16 and 17 and vertically between the wall element 15 and the element 60, forming a part of the drawer element 11, Figs. 2 and 12. Only an outside force properly applied will disengage the combination which is a unit combining the framework, drawer, stack elements, et al.

The way to disengage or open this combination is as follows:

1. Consider the front of the unit to be the side out of which the drawer will slide. That's the side where the drawer curtain 21' is located.
2. Strip 18, Fig. 2, will not permit the drawer to slide out the back way.

3. Put thumbs on the front edges of wall elements 16 and 17.

3. Press tray elements from the back with your free fingers. The press of the free fingers will push the stack elements forward, the stack elements in turn will push the drawer element forward. When the drawer element is withdrawn, the stack elements remain free for removal.

4. Numeral 59 shows an opening framed by notches 40 and 49, Figs. 8 and 11. This feature makes it possible to display the chips in their different colors, which endows the unit with one of its artistic attributes.

5. Figs. 13 to 25, similar to Figs. 1 to 12, expose some variations in the forms herein disclosed. Similar parts of the forms are indicated by similar numerals, and the description hereinabove given with reference to Figs. 1 to 12, indicated by numerals 10 to 60 applies correspondingly

to the Figs. 13 to 25 indicated by numerals 18' to 60'. Additional features in the second set of figures are indicated by numerals 61' to 69' described as follows:

Numerals 61' and 63' indicate an alternate latch, a variation of latch 33 and 34 shown in Figs. 5 and 6.

Here 61' is a bar equal in length to that of wall element 14' which is provided with an opening or slot 62' through it, sufficient to receive snugly said bar 61'.

In the drawer element 11', the end walls 23', 24' and partitions 25', 26' are notched at 65'. Bar 61' bears lugs 63' corresponding to notches 65'. When bar 61' is inserted into opening 62', the lugs 63' respectively fit into the notches 65'. This interfitting between the lugs and the notches establishes an engagement which holds the drawer element 11' securely within the housing element 14', 15', 16', and 17'. The drawer element can be removed from the housing element only after the rod 61' is taken out of the opening or slot 62'.

Numerals 64' indicates a notch on the end of the rod for a nail hold.

Numerals 66' and 67' indicate partitions transversely across the tray elements 12' and 13'. Partition 67' is lower than the main wall elements of the trays in which are incorporated. Partition 66' is higher than the main wall elements of the trays in which they are incorporated. This difference in height between the partitions establishes a transverse engagement between the trays when they are combined face to face or rim to rim in forming the compartment element shown in Figs. 22 and 23.

Numerals 53 and 44, Fig. 11, disclose the transverse engagement in the end walls of the trays.

Numerals 68' and 69' indicate notches in partitions 66' and 67' which like notches 49' and 50' are helpful for the removal of chips from the trays.

Numerals 55' indicate projections near the end of the compartment elements tops as compared to 55 placed more centrally with reference to the tops of the compartment elements. This differentiation makes it possible for element 60', Fig. 21, to engage the elements 55' directly over tray element 12', where in the first disclosure, Fig. 7, element 21' rests in front of tray element 12'.

The result is a combination where the drawer front is flush with the tray fronts, instead of a drawer front in front of the tray fronts.

The invention herein, entirely a new object of manufacture, may be made of any available materials. It is, of course, susceptible to various changes and modifications and adaptable for various uses, the details shown being merely for disclosure and not in limitation. The text herein necessarily is limited in description. Reliance is therefore placed on the accompanying drawings to overcome this limitation at least to some extent by graphic delineation. The right is, hereby reserved to make such adaptations, developments and expansions as properly fall within the scope and purpose suggested by the presentation herein, terminating in the appended claims.

I claim:

1. A combination container comprising a housing element, a plurality of tray elements therein contiguously disposed and stacked in horizontal layers, those of each stack having interfitting parts adapted to prevent horizontal

movement of any one of the stack relative to the others thereof when contained in the housing element, and tray retaining means engaging only one layer of said tray elements within the housing element, whereby all of the tray elements are retained within the housing element.

2. A combination container comprising a housing element, a plurality of tray elements therein contiguously disposed and stacked in horizontal layers, complementary interfitting means between the tray elements of each stack disposed horizontally and both longitudinally and transversely of the tray elements, and tray retaining means engaging only one layer of said tray elements within said container, whereby all of the tray elements are retained within the housing element.

3. A combination container comprising a housing element, a plurality of compartment elements therein contiguously disposed and stacked in horizontal layers, each compartment element consisting of two complementary tray elements, complementary interfitting means between the compartment elements of each stack and complementary interfitting means between the tray elements of each compartment element, disposed horizontal and both longitudinally and transversely of the tray elements, and tray retaining means engaging one end of only one layer of the compartment elements within the housing element.

4. A combination container comprising a housing element, layers of removable compartment elements therein, interengaged longitudinally and transversely, each compartment element consisting of two separable substantially traylike elements contacting each other rim to rim to rim interengaged longitudinally and transversely, and tray retaining means within said housing engaging an end of only one layer of said compartment elements.

5. A combination container comprising a housing element, removable compartment elements, contiguously disposed therein in horizontal layers in stack form, each compartment element consisting of two separable substantially traylike elements contacting each other rim to rim and formed with interengaging elements, engaged longitudinally and transversely, and interengaging elements between contiguous compartment elements within the stacks engaging them longitudinally and transversely, said housing element having tray retaining means engaging an end of only one layer of the compartment elements.

6. A combination container comprising a housing element and removable compartment elements contiguously disposed therein in at least one horizontal layer, each compartment element having substantially a bottom wall element, a top wall element, two side wall elements and two end wall elements for accommodating a plurality of poker chips, each compartment element consisting of two separable substantially traylike elements contacting each other rim to rim and interfitting each other longitudinally and transversely thereof, said housing element having retaining means engaging only one layer of the removable compartment elements.

7. A combination container comprising a rectangular housing element open on one side and having a short wall depending from its top wall,

the latter having a slot extending longitudinally thereof, a plurality of tray elements with ends at the open side in said housing element, having interfitting parts for preventing relative movement lengthwise of the tray elements, a removable drawer slidably mounted in said housing element above said tray elements, said drawer having tray retaining means overhanging the upper forward edge portion of the adjacent tray elements and said short wall overhanging the rear edge portion of said adjacent tray elements, said drawer having also notches in its upper edge communicating with the slot in the top of the housing element, and a removable retaining bar adapted to lie through said slot and having means in engagement with the notches of the drawer, whereby the latter and therewith the tray elements are retained in the housing element by said retaining bar.

8. A combination container comprising a rectangular housing element open at one side and having a short wall depending from the top wall, the latter having a slot extending longitudinally thereof, a plurality of tray elements in said housing with ends at the open side arranged in interconnected tiers, a removable drawer slidably mounted in said housing element above said tray elements, said drawer having a tray retaining apron overhanging the upper forward edge portions of the adjacent tray elements and the short wall overhanging the upper rear edge portion of said adjacent tray elements, said drawer having also notches in its upper edge communicating with the slot in the top of the housing element and a removable locking bar adapted to lie in said slot, and having downwardly projecting lugs entering the notches of the drawer, whereby the latter and therewith the tray elements are retained in the housing element by said locking bar.

9. A combination container comprising a box-like housing element having a partial wall on one side and no wall on the opposite side, a plurality of compartment elements, consisting of 5 interfitted tray elements horizontally disposed and contiguous to each other in said housing element, said compartment elements having interfitting parts for preventing relative movement crosswise and lengthwise, a removable drawer, having retaining means, slidably mounted in said housing element adjacent to the uppermost compartment elements, said compartment elements being interfitted between said partial wall and said retaining means, said housing having means 10 engaging said drawer, whereby said interfitted compartment members become securely retained in said housing element.

10. A combination poker chip holder comprising a case member and a plurality of poker chip container members, disposed contiguously in layers and as stack members in a block embraced within the case member, each container member comprising two paired-up, face-to-face tray elements, means between and within the face limits of the tray elements, preventing their longitudinal and transverse relative movements, 20 contacting container members having between them cooperating elements, preventing longitudinal and transverse relative movements of said container members, the case member having elements engaging only the upper tray elements 25 whereby all of said tray elements are retained in the case member, the block of container members and the case member, thus engaged with each other, constituting the combination poker chip holder.

SAMUEL JOHN STANTON.
